UNITED STATES PATENT OFFICE

2,614,667

PANE FASTENER

Ivan M. Kirlin, Detroit, Mich., assignor to The
Kirlin Company, a partnership

Application June 18, 1949, Serial No. 99,923

5 Claims. (Cl. 189—78)

1

The present application relates to an improved light fixture and more particularly relates to an improved frame and door assembly for flush mounted ceiling lights.

It is an object of the present invention to provide an improved frame and door assembly of the above mentioned type which is simple in construction, economical of manufacture and reliable and efficient in operation.

A further object of the invention is to provide an improved assembly of the above mentioned type including an improved clip for mounting the glass member in the door which clip also functions to prevent undesirable escape of light through the door frame.

Another object of the invention is to provide an improved clip for mounting the glass member in the door frame, which clip also serves to reinforce the corners of the door frame.

It is also an object of the invention to provide an assembly of the above mentioned type including improved means for mounting the door within the fixed frame which means permits an improved close fit between the door frame and the fixed frame.

Other and more detailed objects of the invention will become apparent from a consideration of the following specification, the appended claims and the accompanying drawing, wherein:

Figure 1 is a view in perspective showing a frame and door assembly constructed according to the present invention mounted in a ceiling;

Fig. 2 is a sectional view of the construction illustrated in Fig. 1, taken along the line 2—2 thereof;

Figs. 3 and 4 are enlarged sectional views of the construction illustrated in Fig. 2 taken respectively along the lines 3—3 and 4—4 thereof; and,

Fig. 5 is a view in perspective of the clip employed in the construction illustrated in Figs. 1, 2, 3 and 4.

It will be appreciated from a complete understanding of the present invention that the improvements thereof may be readily embodied in equipment of widely different types and designs. In an illustrative but not a limited sense, the improvements of the present invention are herein illustrated and described as embodied in a frame and door assembly for a flush mounted ceiling light. It will also be appreciated that the term "ceiling light" refers broadly to the type of light conventionally mounted in ceilings but which, of course, may be also readily mounted in walls or any other similar surface.

2

Referring to the drawing, the assembly of the present invention generally comprises a fixed frame 10 adapted to be flush mounted in a ceiling 12, a door frame 14 pivotally mounted in the fixed frame 10, a glass member 16 and a plurality of clips 18 mounting the glass member 16 in the door frame 14.

In the preferred embodiment illustrated in the drawing, the fixed frame 10 is square and defines a large square opening 20. The frame 10 is shaped to define a square recess 22 in its lower face, as viewed in Figs. 1 and 2. Adjacent one side of this recess the adjacent walls of the recess are provided with slots 24 extending at right angles to the adjacent recess wall and disposed adjacent the outer or lower face of the frame 10 as viewed in Figs. 1 and 2.

The door frame 14 is also square and adapted to closely fit within the recess 22. The frame 14 in the embodiment illustrated is formed of a single strip of sheet metal, which in cross section is similar to conventional angle iron and includes flanges 26 and 28. The frame 14 is formed by bending the flange 28 to define the four outer walls of the square frame 14 and mitering the flange 26 adjacent the bends in the flange 28 so that the adjacent mitered edges 30 and 32 of the flange 26 are disposed substantially in abutting engagement when the frame 14 is in its finished shape. The ends of the strip from which the frame 14 is formed are secured together by spot welding overlapping end portions of the flange 28.

The door frame 14 is pivotally mounted on the frame 10 by means of rivets 34 extending through the slots 24 provided in the frame 10 and extending through circular apertures 36 provided in the flange 28 of the frame 14 and adapted to register with the slots 24 when the door frame 14 is received in the recess 22 with the outer surface of its flange 26 disposed substantially flush with the outer surface of the frame 10. The rivets 34 serve as pivot pins, permitting the door frame 14 to be moved pivotally relative to the fixed frame 10 and are also adapted to slide longitudinally of the slots 24 to permit the door to be moved bodily relative to the frame 10 as soon as the door has been opened slightly. By virtue of the bodily movement thus permitted, interference between the frame 14 and the frame 10 is prevented, even though the frame 14 is proportioned to closely fit the recess 22 in the frame 10.

The clip 18 of the preferred embodiment illustrated in the drawing is stamped from a flat strip of sheet metal. As best illustrated in Fig.

5, spaced portions 38 of the clip are turned upwardly to provide flanges disposed in perpendicular planes. These flanges are integrally interconnected by a flat web or intermediate portion 40. The clip also includes a pair of spaced finger portions 42 integral with the flange portions 38 and disposed in the plane of the intermediate portion 40 and extending at right angles to each other. In use, the clip, in the shape just described, is placed in one of the corners of the door frame 14 with the flanges 38 overlying portions of the flange 28 of the frame 14 to which they are spot welded or otherwise suitably secured, and with the intermediate portion 40 in engagement with the flange 26 of the frame 14 and overlying the abutting mitered edges 30 and 32 as best illustrated in Fig. 3. It will now be appreciated that in this position, the intermediate portion 40 of the clip serves to prevent the passage of light between the abutting mitered edges of the flange 26. As is clearly illustrated, the flanges 38 engage and are secured to the flange 28 of the frame 14 in spaced relation to the corner of the frame, thus avoiding interference with the rivets 34 in the corners of the frame 14 in which the rivets are mounted. After the flanges 38 have been secured to the frame 14, the finger portions 42 are deformed upwardly by bending them along the lines indicated in Fig. 5 in broken lines at 44. The glass member 16 is then placed in the frame 14, fitting inside of the finger portions 42 of the clips at each corner of the frame and then finger portions 42 are bent inwardly along the lines indicated at 46 in broken lines in Fig. 5, to the position illustrated in Figs. 2, 3 and 4, and illustrated in broken lines in Fig. 5. In this position, as illustrated in Fig. 2, the outer end portion of the fingers 42 beyond the fold line 46 overlies the marginal portion of the inner face of the glass member 16 to securely hold the latter in place. As illustrated in Fig. 2, the outer face of the glass member 16, at each of its corners, engages the intermediate portion 40 of the clip 18, the glass member 16 thus being entirely supported by the clips 18.

In the embodiment illustrated in the drawing, the door frame 14 may be secured in the closed position illustrated in the drawing by a member 48 extending through an aperture provided in the frame 14 and having a threaded engagement (not illustrated) at its inner end with the fixed frame 10, and having a knurled portion on its outer end for facilitating rotation thereof.

While only one specific embodiment of the invention has been illustrated and described in detail herein, it will be readily appreciated that numerous modifications and changes may be made therein without departing from the spirit of the present invention.

What is claimed is:

1. An assembly for a lighting fixture, said assembly comprising a frame defining an aperture and including frame portions at each side of said aperture disposed in the plane of said aperture, the ends of adjacent of said frame portions abutting each other at the corners of said frame, a glass member for closing said aperture when overlying said frame portions, and clips individual to said corners and secured to the inside surface of said frame in a position to overlie the inside surface of the abutting ends of said frame portions to prevent the passage of light therebetween without marring the exterior ap-

pearance of the frame, and fingers on said clip for holding said glass member in said frame.

2. An assembly for a lighting fixture, said assembly comprising a frame defining an aperture and including frame sections at each side of said aperture of angular cross section and having one flange thereof disposed in the plane of said aperture and the other flange extending at right angles to said flange at the outer edge thereof, the ends of said one flange of adjacent of said frame sections abutting each other at the corners of said frame, said frame receiving a glass member for covering the aperture thereof, and clips individual to said corners on the inner face thereof and having a pair of flanges extending parallel and secured to said other flange of each of the adjacent of said frame sections adjacent the intersection thereof and including an intermediate portion disposed parallel to the plane of said aperture and overlying the abutting ends of said one flange of the adjacent frame sections to prevent the passage of light therebetween, said clips having fingers disposed in the plane of the intermediate portion and normal to said flanges in position to be bent parallel thereto for receiving said last member therebetween and to be bent over the corners of the glass member thereafter to secure the glass member in position within the frame.

3. A clip having a diagonal web and upstanding flanges at the ends, the ends and flanges being disposed at an angle of 45° to the side edges of the web thereby positioning the flanges in planes disposed at an angle of 90° to each other, and fingers extending from said flanges in a position normal thereto when disposed in the plane of the web.

4. A clip having a web with upstanding flange portions at the ends disposed at an angle of 45° to the side edges of the web, one of which side edges is shorter than the other side edge, and a finger extending normal from each flange portion and disposed in the plane of the web.

5. A clip having a web with upstanding flange portions at the ends disposed at an angle of 45° to the side edges of the web, one of which side edges is shorter than the other side edge, and a finger extending normal from each flange portion and disposed in the plane of the web, said fingers being bendable into a position parallel to its respective flange portion.
